UNITED STATES PATENT OFFICE.

JAMES HARVEY FRENCH, EDWIN JAMES FRENCH, AND WILLIAM BERNARD FRENCH, OF DEFIANCE, OHIO, ASSIGNEES OF ONE-HALF TO SAID EDWIN JAMES FRENCH, ONE-FOURTH TO SAID WILLIAM BERNARD FRENCH, AND ONE-FOURTH TO SAID JAMES HARVEY FRENCH.

PORTABLE MORTISER.

Application filed July 17, 1922. Serial No. 575,685.

To all whom it may concern:

Be it known that we, JAMES HARVEY FRENCH, EDWIN JAMES FRENCH, and WILLIAM BERNARD FRENCH, citizens of the 5 United States, residing at Defiance, in the county of Defiance and State of Ohio, have invented certain new and useful Improvements in Portable Mortisers, of which the following is a specification, reference being 10 had therein to the accompanying drawings.

This invention relates to a portable hand mortising machine and it has for its object to provide a highly efficient device of this character adapted to be secured to the edge 15 of a door that is in place and which will serve to rapidly and neatly mortise the front edge of the door for the reception of a lock.

It is a further object of the invention to provide a machine of the character indicated 20 which may be accurately controlled both as to the length and depth of the cut. Another object of the invention is to provide a machine of the character described arranged in such manner that the strain will be im- 25 parted to the rear edge of the door whereby all possibility of splitting the front stile of the door will be eliminated.

Further objects and advantages of the invention will be more particularly set forth 30 in the detailed description which follows.

In the accompanying drawings:

Fig. 1 is a left side elevation of a machine constructed in accordance with the invention showing the same mounted in operative position upon a door;

Fig. 2 is a horizontal sectional view upon line 2—2 of Fig. 1;

Fig. 3 is a fragmentary horizontal sectional view upon line 3—3 of Fig. 1;

Fig. 4 is a right side elevation of the machine;

Fig. 5 is a longitudinal vertical sectional view therethrough; Fig. 6 is a detail sectional view across the slide bar; and Fig. 7 is 45 a detail plan view of a modified form of clamp hereinafter described.

Like numerals designate corresponding parts in all of the figures of the drawings.

In the drawings 5 designates the front stile, 6 one of the rails and 7 the rear stile 50 of a door to be mortised.

The machine of the present invention comprises a saddle block 8 and a carriage 9 mounted for vertical step-by-step movement upon the saddle block as hereinafter set 55

forth. A clamping mechanism at the upper end of the saddle block comprises a pair of arms 10 which are pivoted to the saddle block at 11 and are moved forcibly toward and from each other by rotation of a 60 right and left screw 12 having an operating thumb piece 13 upon one end thereof. The screw 12 engages in round nuts 13^a which are seated in recesses 14 of the arms 10 and are held in place by plates 15. The arms 65

10 are preferably rubber tipped, as indicated at 16 and in the initial application of the machine to a door, the operator grasps a handle 17 which is mounted upon the top 70 of the carriage 9 and places the machine in position with the arms 10 embracing the front edge of the door and lying upon opposite sides of the stile 5.

At the same time the cutter or chisel 18 is entered in an opening 19 which has been bored in the stile 5 75 with an ordinary brace and bit. By turning the screw 13 the machine as a whole may be temporarily positioned upon the door. The clamping mechanism at the top constituted by the arms 10 and associated parts is 80

intended merely for the purpose of positioning the machine upon the door during the time that more powerful securing means are being placed prior to the beginning of the cutting action. The more powerful retaining means referred to consists of chains 20, threaded hooks 21 and thumb nuts 22 upon said threaded hooks. Only one chain and hook are shown in Fig. 1 but it is to be understood that this structure is duplicated 90 upon the opposite side of the door.

The rear portions of the chains are engaged with the hooked ends 23 of a U shaped yoke 24 the intermediate portion of which is pivoted at 25 upon a saddle plate 26. 95 This saddle plate is adapted to extend across

the rear or hinged edge of the door and to be temporarily secured in place by a nail 27 which is passed through an opening formed in said saddle plate and driven a short distance into the rear stile 7 of the door. It is to be noted that the chain 20 is inclined slightly downward from the rear edge of the door to the front edge thereof and by tightening the thumb nuts 22 the machine as a whole may be very securely bound against the front edge of the door beyond the possibility of any downward slipping of the same. The machine having been set for depth and length of cut, as hereinafter set forth, the operator then imparts a swinging movement to the operating handle 28 which is mounted upon a transverse shaft 29 and carries a segmental gear 30. This gear meshes with a rack 31 formed upon the upper face of a slide bar 32 within which the cutter 18 is adjustably mounted. It will readily be understood that a swinging movement of the handle 28 will impart longitudinal reciprocation to the slide bar 32 to force the cutter 18 into the door and to withdraw the cutter from the door. The movement of the cutter out of the mortise in the door is limited by a stop screw 33, the tip end 33^a of which is disposed in a groove 32^a milled in the underside of the slide bar 32. An adjusting screw 34 has threaded engagement with the shank portion 35 of the cutter 18 and this screw is held against endwise movement by a collar 36 which lies between the rear end of the slide bar 32 and a block 37 carried upon the rear end of said slide bar. It is manifest that turning movement of the screw 34 will adjust the cutter 18 longitudinally of the slide bar. This renders it possible to compensate for variations in the length of the cutter due to the shortening of the same by sharpening.

The swinging movement of the handle 28 not only serves to impart a back and forth movement to the cutter 18 but it imparts a step by step feeding movement to the carriage 9 by which the cutter is carried so that at each stroke of the cutter the cut made will be at a little higher point, usually about one-eighth inch, above the point at which the preceding cut was made. This is accomplished by providing upon a cover plate 9^a of the carriage 9 a feed mechanism consisting of a plunger 38 which is mounted to slide through a guide plate 39. This plunger is periodically engaged by a pin 40 upon the collar 39^a and when this plunger is forced inwardly it rocks a bell crank lever 41 upon its pivot 42. A dog 43 is pivotally mounted at 44 upon the bell crank lever 41, said dog moving into engagement with the teeth 45 of a rack bar 46 upon initial downward movement of said dog. Thereafter movement of the bell crank lever 41 acts to lift the carriage 9 bodily, though by this time the cutter

18 has been withdrawn from the mortise in the door. The carriage 9 is held at the point to which it is lifted by a pawl 47 which is pivoted at 48 and is provided with a thumb piece 49. A spring 50 acts to move the pawl 47 into engagement with the teeth of the rack 46. A spring 51 acts against the bell crank lever 41 and tends to move the plunger 38 to the right in Fig. 1, when the handle 28 is pulled rearwardly on its cutting stroke and the pin 40 moves away from plunger 38. The result of this is to lift the dog 43 preparatory to said dog taking a fresh hold on the teeth of rack 46 but at this time the dog 43 engages a pin 52 carried by the cover plate 9^a which pin acts to hold the dog out of engagement with the teeth of the rack bar until, upon initial downward movement of the bell crank lever the said dog is bodily lowered far enough to permit its engaging end to move inwardly beneath the pin and into engagement with the teeth of the rack. The purpose of this construction is to facilitate the lowering of the carriage after the operation of forming one mortise has been completed and it is desired to reset the machine preparatory to cutting another mortise. When this is to be done the operator supports the weight of the carriage by grasping the handle 17 and presses against the thumb piece 49 against the tension of spring 50 to disengage the pawl 47 from the rack bar. Since at this time the dog 43 is held out of engagement with the rack bar by the pin, it follows that there is nothing to prevent bodily downward movement of the carriage in the ways 53 of the saddle block 8, said carriage being provided with a dovetail rib 54, see Fig. 2, which is slidably disposed in said ways. A stop plate 55 limits downward movement of the dovetail rib 54. A keeper lug 56 formed upon the stop plate 55 is adapted to be engaged by the lower end of a latch lever 57 which is pivoted at 58 upon the cover plate 9^a. The function of the latch lever 57 is to lock the carriage at its lower limit of movement. If this latch were not provided the carriage would ride to the upper end of the ways 53 whenever the user tried to lift the machine by grasping the handle 17. At this time the latch 57 acts to lift the saddle block with the carriage and to maintain all of the parts in set position during the time that the machine is being applied to a door. However, upon initial downward movement of the bell crank lever 41, a roller 59 upon the inner side of the lower arm of said bell crank lever rides over the beveled upper end 60 of the lever 57 and moves said lever against the tension of a spring 61 to disengage its lower end from the keeper lug 56. Before the lever 57 again returns to its initial position under the influence of spring 61 the carriage will have been lifted one notch and thus the hooked

lower end of the lever 57 will not be able to again engage under the keeper lug 56.

For supporting the machine in an upright position when not in use laterally projecting feet 62 are provided upon the saddle block, see Fig. 2, and these feet are provided with rubber tips 63 which in conjunction with a corresponding rubber tip 64 carried by the head of the screw 33, constitute feet for the machine.

To adjustably limit the movement of the cutter 18 into the door and to consequently determine the depth of the mortise being cut, we provide upon the right hand side 15 of the carriage 9, see Fig. 4, a swinging collar 65 which carries a stop 66 for the handle 28 and a slotted segment 67. The slotted segment is adapted to be bound in varying positions of adjustment by a clamp- 20 screw 68 having a handle 69, in a manner well known in this art. It is manifest that adjustment of the collar 65 will position the stop 66 to stop the handle 28 in its downward movement, at any desired point 25 and that this will, in turn, limit the inward movement of the slide bar 32 and cutter 18. The operator may set the cutter to the desired depth by adjusting the handle 28 to such position as will bring the proper graduation 30 of the series of graduations 70 upon the slide bar 32 in alignment with the rear edge of the carriage 9. If, for example, it be desired to make a mortise three inches 35 in depth, the graduation "3" will be brought into alignment with the rear edge of the carriage 9 and this will indicate to the operator that the cutter will then be projected three inches into the door when the handle 40 is moved to its limit of movement outwardly and downwardly. After having brought the handle 28 to the position to set the graduation "3" in alignment with the rear edge of the carriage 9, the operator will loosen the clamp screw 68 and the weight of 45 the segment 67 will cause the stop 66 to move around to the position then occupied by the handle 28 and to abut said handle. The clamping screw 68 will then again be tightened and thereafter the handle 28 will be 50 limited upon each stroke to a return to the position that it occupied at the time of the setting of the cutter.

The length of the mortise to be cut is determined by the setting of a slidable gauge 55 71, see Figs. 1 and 2, along the rack bar 46. This rack bar is provided with graduations with which said gauge coacts, said graduations being indicated at 72, and when the gauge has been set at the graduation marked, 60 say 4, an apron 73 constituting a part of the gauge will have been moved to such position as to cover those teeth of the rack 46 above the point at which the pawl 47 will be located when a cut of that length has been 65 completed. In other words, when the cut

of the desired length has been completed and the pawl 47 has reached the lower edge of the apron 73 it can no longer engage the teeth of the rack bar because said teeth are covered by the apron and thus, even though 70 the handle 28 be manipulated further, the carriage will not travel any further upwardly and no additional cutting will take place. A binding screw 74 provides means for binding the gauge 71 in the position to 75 which it is adjusted. By referring to Fig. 5 it will be seen that the cutter 18 is semicircular at its upper portion but is provided along its lower edges with a flat vertical portion 18^a. This flat vertical portion overlaps 80 the juncture between the pieces being cut at each stroke of the cutter 18 and serves to plane the surface, leaving it perfectly smooth.

It is a well known fact that cutters or 85 chisels of the character indicated are not likely to break or to become chipped if the thrust upon them is a direct, straight line, thrust but that they are very likely to become broken if there is the slightest twisting action imparted to them. To guard 90 against looseness of the slide bar 32 in its ways and to insure that the thrust of this slide bar will always be a direct, straight, line thrust upon the cutting tool, we mount 95 a friction strip or gib 75 in a groove 76 formed in the inner face of the cover plate 9^a. Adjusting screws 77 accessible from the exterior face of the cover plate, see Figs. 1 and 6, are provided with lock nuts 78 and 100 with slotted heads 79. These screws are threaded into the cover plate 9^a and they are mounted to turn with respect to the friction strip or gib 76. It is manifest that by 105 screwing inwardly upon the screws 77 the strip 76 may be caused to frictionally bind against the slide bar 32 and to prevent any looseness whatever of said bar. This structure additionally has the advantage of placing 110 such friction upon the bar 32 as to cause the handle 28 to remain in any position to which it may be moved, instead of dropping downwardly with a bang every time it is released for a moment.

Referring to Fig. 5 it will be seen that an 115 angular portion 18^b is formed upon the cutting tool between the shank 35 and the cutting portion of the tool. This angular portion 18^b engages in a correspondingly shaped portion 32^b of the slide bar 32 and 120 thus the cutting tool is positively held against any tendency to turn with respect to the slide bar.

In Fig. 7 we have illustrated a modified 125 form of clamp which may be used at the top of the saddle block in lieu of the clamp shown. This clamp comprises arms 10^a pivoted at 11^a and engaged by the right and left threaded portions of screw 12^a. The screw is held against endwise movement by 130

a collar 12^b thereon engaging a fork or spaced lugs 12^c. The screw is engaged with round nuts 13^b which engage the arms 10^a in the manner hereinbefore set forth.

5 From the foregoing description it will be seen that a machine adapted to serve the purposes set forth has been provided, comprising elements which are of simple and economical construction, powerful and reliable in operation and capable of manipulation with the expenditure of minimum time and labor upon the part of the operator.

10 It is to be understood that the illustration 15 in the accompanying drawings is for purposes of explanation of the principles involved, only and that the invention is not limited to the precise construction set forth but that it includes within its purview whatever changes fairly come within either the terms or the spirit of the appended claims.

20 Having described our invention what we claim is:

25 1. The combination with a door mortising machine adapted to fit flat against the front edge of a door, of a saddle plate adapted to rest flat against the rear edge of the door, a pivoted U shaped yoke carried by the saddle plate and having hooked terminal ends, chains engageable with said hooked terminal ends and means for engaging the other ends of the chains with the door mortising machine and for exerting a drawing action thereon.

30 35 2. A machine of the character described comprising a vertical saddle block adapted to rest against the front edge of a door, a carriage in the form of a rectangular block having a cover plate on one side and having 40 slideable engagement with the saddle block at its front end, a rack bar carried by the saddle block, a toothed mechanism supported upon the cover plate of the carriage and acting upon said rack bar to impart a vertical step by step movement to the carriage with respect to the saddle block and feet formed complementally upon the bottom of the saddle block and upon the carriage for supporting the machine in an upright position when not in use.

45 50 55 3. A machine of the character described comprising a vertical saddle block adapted to rest against the front edge of a door, a carriage in the form of a rectangular block having slideable engagement with the saddle block at its front end, means for securing the saddle block to the door, a rack bar carried by the saddle block, a toothed mechanism supported upon the cover plate of 60 the carriage and acting upon said rack bar to impart a vertical step by step movement to the carriage with respect to the saddle block, a shaft disposed transversely in the carriage, a gear housed in the carriage, a handle upon the shaft outside of the car-

riage and swinging in a vertical plane, said gear being mounted upon said shaft, a slide bar mounted for reciprocation in the carriage and toothed for engagement by said gear and a cutter projecting from the forward end of the slide bar and through the saddle block, said saddle block being vertically slotted to permit of reciprocation of the cutter and vertical movement of the carriage and cutter in the formation of a vertical mortise in the front edge of a door.

70 75 80 85 90 95 100 105 110 115 120 125 130 4. A device of the character described comprising a vertically slotted saddle block, means for securing the same to the front edge of a door, a vertically traveling block having slideable engagement with the saddle block and lying in the plane of the door to be mortised, said block having a hollow interior constituting a housing, a pinion housed in said block, a shaft by which said pinion is carried and which shaft projects laterally through the block, a handle upon the outer end of said shaft mounted to swing in a vertical plane, a slideable rack bar mounted in said block and engaged with said gear, a cutter carried by said rack bar and projecting through the slotted portion of the saddle block, means for securing said saddle block to the front edge of a door to be mortised and with said saddle block lying in the plane of said door, said cutter being laterally centered with respect to the saddle block and vertically traveling block, a handle upon the top of the vertically traveling block, means for imparting a step by step vertical movement to the vertically traveling block along the saddle block, locking means for locking the vertically traveling block to the saddle block when the former is at its lower limit of movement and means for releasing said locking means upon initial movement of said handle.

125 130 135 140 145 150 155 160 165 170 175 180 185 190 195 1. A device of the character described comprising a vertically slotted saddle block, means for securing said saddle block to the front edge of a door, said saddle block having a dove-tail channel formed in its outer face, a block having a rib seated in said channel to slidably mount the block with respect to the saddle block, said block constituting a vertically movable carriage and said block having an interior cavity constituting a housing, a toothed gear in said housing, a rack bar slideable through the lower portion of the block, a cutter longitudinally adjustable with respect to the rack bar, a shaft by which the gear is carried, a handle upon the outer end of said shaft, said handle swinging in a vertical plane, a cover plate for the said cavity, mechanism carried by the cover plate and having operative engagement with said handle for imparting a vertical step by step movement to the saddle block and a stop carried by the said block adjustable to varying positions for

limiting the movement of the handle and consequently for limiting the throw of the rack bar.

6. A structure as recited in claim 5 wherein the means for imparting a vertical step by step movement to the block includes a graduated rack bar, operating pawls engaging the same and means adjustable along the rack bar for throwing said pawls

out of action when said pawls reach the position determined by the adjustment of said means.

In testimony whereof we hereunto affix our signatures.

JAMES HARVEY FRENCH.

EDWIN JAMES FRENCH.

WILLIAM BERNARD FRENCH.
